UNITED STATES PATENT OFFICE.

CHARLES DINES SEVIER AND FRANK PETER ECKROAT, OF FORT COLLINS, COLORADO

VALVE TOOL.

1,422,890.

Specification of Letters Patent. Patented July 18, 1922.

Application filed January 19, 1921. Serial No. 438,491.

To all whom it may concern:

Be it known that we, CHARLES DINES SEVIER and FRANK PETER ECKROAT, citizens of the United States, and residents of Fort 5 Collins, in the county of Larimer and State of Colorado, have invented certain new and useful Improvements in Valve Tools, of which the following is a specification.

Our invention is an improvement in valve 10 tools. An important object of our invention is to provide a valve tool which will effectively remove the inner valve stem from the valve casing when the lugs on the valve stem have been broken off and when the 15 valve stem has been broken off below the plug.

A further object of our invention is to provide a device as above named which will be inexpensive to manufacture and simple of 20 construction.

In the accompanying drawings forming a part of this specification and in which like numerals are employed to designate like parts throughout the same,

25 Figure 1 is a sectional view of the tire valve showing the tool applied in one of its uses,

Fig. 2 is a view partly in section showing the tool in another position in the valve 30 casing, and

Fig. 3 is a perspective view of the device embodying our present invention.

In the drawings 1 designates the valve casing which is screw-threaded on its upper 35 end as at 2. The casing is screw-threaded internally to receive the plug 3 on the valve stem 4. The plug 3 is provided with lugs 5 and 6.

The above is a brief description of the up- 40 per portion of the ordinary tire valve.

The device comprising our present invention is shown in Fig. 3, in which 7 represents the main body portion of the tool. One end of the tool is slotted longitudinally as shown 45 at 8 forming the resilient fingers 9 and 10. The opposite end of the tool is screw-thread-

ed as at 11, the threads being left-hand threads and of extreme high pitch in order to produce a firm grip on the plug 3 when this end of the tool is inserted therein and 50 turned.

The grip 12 provides a finger grip for turning the tool and is either welded or pressed on the body portion 7.

In use the operation is as follows: 55

If the lugs 5 and 6 have been broken off the top of plug 3 as may occur through attempting to seat the same too snugly in the valve casing, making it impossible to remove the plug with the ordinary valve tool, the 60 resilient fingers 9 and 10 of the tool are inserted in the end of the valve casing 1 until the fingers rest upon the top of the plug 3 with the valve stem 4 between the fingers. By exerting firm pressure on the fingers with 65 pliers P or the like, and giving several quick movements to the right and left, the valve stem may be severed near the bottom of the plug. The other end of the tool is now employed to extract the plug 3. This is done 70 by simply inserting the threaded end 11 into the plug and turning the same to the left. When the threads firmly grip the inner walls of the plug 3 said plug will move to the left and will be finally ejected from the valve 75 casing. The grip 12 serves as a finger grip to turn the body of the tool.

It is to be understood that various changes may be made in the size and shape of our invention without departing from the spirit 80 of the invention or the scope of the subjoined claim.

We claim:

In a valve tool, a cylindrical body, one end of said body being tapered and screw-threaded on the tapered portion, the other end being bifurcated to form resilient fingers, and a grip mounted on the body, as and for the purposes set forth. 85

CHARLES DINES SEVIER.
